UNITED STATES PATENT OFFICE.

ERNEST A. GOSNELL, OF BURKBURNETT, TEXAS.

CLAMP.

1,410,804.

Specification of Letters Patent. Patented Mar. 28, 1922.

Application filed September 22, 1921. Serial No. 502,555.

To all whom it may concern:

Be it known that I, ERNEST A. GOSNELL, a citizen of the United States, residing at Burkburnett, in the county of Wichita and 5 State of Texas, have invented certain new and useful Improvements in Clamps, of which the following is a specification.

This invention relates to new and useful improvements in clamps of the type wherein 10 their grip is increased upon an object during any tendency of the object to free itself from the clamp, and one which will effectively retain its grip upon an object after being engaged therewith.

15 Another object of the invention is to provide a clamp embodying a movable gripping jaw or wedge and means associated therewith for guiding and placing the jaw in co-operative relation with the clamp to grip 20 an object.

Other objects and advantages of the invention will become apparent during the course of the following description.

In the accompanying drawings forming 25 a part of the application and wherein like numerals are employed to designate like parts throughout the several views,

Figure 1 is a perspective view of the invention,

30 Figure 2 is a longitudinal section through the clamp,

Figure 3 is a bottom plan of the wedge, and

Figure 4 is an end elevation of the body 35 portion or cooperation jaw portion.

In the drawing wherein for the purpose of illustration is shown the preferred embodiment of my invention, the numeral 5 designates a jaw or body portion which 40 consists of a substantially square base piece 6 having its top face 7 provided with a longitudinally extending groove 8. Extending upwardly from the base and along opposite longitudinal edges thereof are a pair of 45 guide flanges 9 which by being equipped with outwardly and downwardly inclined inner walls 10 provide the body portion with a longitudinally extending dove tail passage as clearly seen. Each flange 9 is provided 50 with an inwardly extending lip portion 11, it being noted that the longitudinal inner edges of these lip portions are arranged in spaced parallel relation for a purpose which will presently appear. The surface 7 of

the body portion 6 at its juncture with the 55 inclined walls of the flanges 9 is provided with longitudinally extending grooves 12 for the reception of a wedge operator which will later be featured.

The movable jaw or wedge of the device 60 12 consists of a substantially rectangular block 13 tapered in thickness from one end to the other. The top face of the wedge as clearly shown in Figure 1 is provided with a longitudinally extending centrally arranged 65 bead or raised portion 14, the longitudinal edges of which are adapted to slidably engage the longitudinal inner edges of the flange lips 11. The under face of the wedge is provided with a centrally arranged 70 longitudinally extending groove 15, the walls of which are roughened or knurled for gripping purposes. The underface of the wedge along its longitudinal edges thereof is grooved as at 16 to cooperate with the 75 grooves 12 of the body portion to form passages for the wedge operating means which will now be described.

This wedge operating means consists of a substantially U-shaped member 17, the 80 arms 18 of which are adapted to extend in parallel relationship and to slide in the grooves 12 of the body portion. The free end of each arm 18 is provided with a head 19 which is rigidly secured thereto to form 85 abutments for engagement with the large end of the wedge 13. A hook or any other form of attaching device, 20 may be associated with the arched portion of the wedge mover 17 for the purpose of anchoring the 90 clamp to an object. In the present instance, the hook 20 consists of a single strand of material having its intermediate portion formed into an eye 21 through which is adapted to pass the wedge mover 17. The 95 hook is also provided with a pair of approximately parallel arms, each terminating in a hook portion 22 as clearly seen. The numeral 23 designates a rod upon which the device is clamped and it will of course be 100 obvious that the rod may be substituted for a cable or any other object upon which a grip is desired to be attained.

Figure 1 illustrates the invention in an assembled position with the wedge 13 properly associated with the body portion to firmly grip the rod 23 and maintain the clamp in fixed relation thereto. However,

when it is desired to remove the wedge, to cause the device to release its grip upon the rod, the wedge lever 17 is caused to slide in the clamp so that its arched portion will abut the small end of the wedge and cause its removal from the dove tail passage through the body portion whereby the grip formerly exerted upon the rod 23 is released.

- 10 To assemble the wedge in the dove tailed passage of the body portion, the wedge mover 17 is moved so as to dispose the heads 19 remote from the body portion whereby the wedge may be positioned upon the arms 15 of the mover and also upon the rod 23 adapted to be gripped by the device. The mover is then actuated to cause the head 19 thereof to abut the wedge and slide it into the dove tail channel of the body portion 5 where it 20 will be firmly gripped by the walls of the dove tail channel and firmly clamped against the rod 23. The hook 20 may then be anchored to an object so that the mover 17 is retained in position to prevent accidental 25 displacement of the wedge.

The foregoing description and accompanying drawings have reference to what might be considered to be the approved or preferred form of my invention. I desire it 30 to be understood that I may make such changes in the construction, combination and arrangements of parts material, dimensions, etc. as may prove expedient and fall within the scope of the appended claims.

35 Having thus fully described my invention, what I claim as new and desire to secure by Letters Patent, is:

1. A clamp comprising a body portion, a wedge mover slidably mounted in the body portion, and a wedge carried by said mover and adapted for cooperation with the body portion, said mover having means at either

end thereof for engagement with the wedge for placing and displacing the same.

2. A clamp comprising a body portion 45 having a wedge receiving pocket therein, a wedge adapted to be received in said pocket, and a wedge mover slidably mounted in the pocket and adjusted to support the wedge when in an inoperative position.

50 3. A clamp comprising a body portion, a wedge mover slidably associated therewith, and including a pair of spaced arms having heads at one end, and a wedge carried by said mover and adapted for cooperation with 55 the body portion.

4. A clamp comprising a body portion, a wedge mover slidably associated therewith and comprising a U-shaped member, the arms of said member being arranged in 60 spaced relation and equipped with heads, and a wedge removably associated with said member and adapted for cooperation with the body portion.

5. A clamp comprising a body portion 65 having a channel extending therethrough, a wedge adapted to be received in said channel, and a wedge mover slidably associated with the channel and consisting of a U-shaped member the arched portion of which 70 is engaged with one end of the wedge for displacing the same from the body portion, and the free ends of the U-shaped member being provided with heads adapted for engagement with the other end of the wedge 75 whereby it can be moved into an operative position into the said channel.

In testimony whereof I affix my signature in presence of two witnesses.

ERNEST A. GOSNELL.
